(57) **CLAIM**

The ornamental design for a pitcher, as shown and described.

DESCRIPTION

FIG. 1 is a perspective view of a pitcher illustrating our new design;

FIG. 2 is a side view of the design of FIG. 1;

FIG. 3 is a front view of the design of FIG. 1;

FIG. 4 is a rear view of the design of FIG. 1;

FIG. 5 is a top view of the design of FIG. 1; and,

FIG. 6 is a bottom view of the design of FIG. 1.

The broken lines represent portions of the structure that form no part of the claim.

The small circles inside the lower portion of the pitcher represent fluid droplets falling into a pool of fluid represented by the wavy line.
